BLUE FLAME WICKLESS OIL BURNER

Gabriel Grobard, Hartford, Conn.

Application November 10, 1932, Serial No. 641,727

9 Claims. (Cl. 158—87)

This invention relates to blue flame wickless oil burners of the type having fuel grooves and combustion chambers thereabove and communicating therewith, the combustion chambers being formed by concentric perforated shells.

An aim of the invention is to provide an improved oil burner of this type which is highly efficient in operation in that a maximum amount of heat may be derived from a given amount of hydrocarbon, and a steady uniform flame of the desired intensity may be produced in the several combustion chambers. In accordance with my improved arrangement, there are provided a number of angularly spaced apart fuel grooves and a centrally located vaporizing cup, together with means for uniformly distributing the fuel admitted to the cup in the correct proportions to spaced points of the several fuel grooves, thus assuring that each unit of the burner will function with maximum efficiency and with a uniform, steady, continuous, annular flame. Furthermore, in accordance with the present invention, the arrangement is such that the correct proportion of air is mixed with the vapor within the combustion chambers in order to insure complete combustion and maximum efficiency, which means that the burner will operate without smudging or smoking or giving off any obnoxious gases.

A further aim of the invention is to provide an improved arrangement of this sort wherein the various grooves and channels, through or to which the fuel is admitted, may be very easily and readily cleaned.

A further aim of the invention is to provide an improved burner which is characterized by its compactness in arrangement as compared to its high efficiency, which is relatively simple and economical in construction, and which requires practically no care.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings, wherein I have shown, for illustrative purposes, one of the embodiments which the present invention may take:

Figure 1 is a top plan view of the burner base with the cover therefor, a portion of the latter being broken away;

Fig. 2 is a sectional view taken substantially

on line 2—2 of Fig. 1, portions of the perforated shells being shown by broken lines;

Fig. 3 is a sectional view through the burner base taken substantially on line 3—3 of Fig. 1; and

Fig. 4 is a view of the cover for the vaporizing cup and channels.

Referring to the drawings in detail, the base, which is preferably of a single casting, is shown as having a plurality of fuel grooves 10 angularly spaced apart preferably at like distances from the center of a centrally located vaporizing cup 11. In the present instance, three such fuel grooves are illustrated, but, obviously, the number thereof may be varied, if desired. Each of the fuel grooves is preferably of annular form and has an exterior wall 12 and an interior concentric wall 13. These walls are provided, below their upper edges, with ledges 14 upon which the usual perforated shells 15 and 16 rest. Traversing the center of each ring in which a fuel groove is formed is a diametrically extending channel 17 which opens at its opposite ends into the fuel groove. Each of these channels has side walls 18 on the opposed surfaces of which are shoulders 19 on which an arm of the cover, hereinafter described, is adapted to rest. These channels are arranged in radiating relation with respect to the center of the base. Between the cross bar on which the channel is formed and the ring in which the fuel groove is formed are parti-circular air openings 20 of sufficient size to insure admission of the correct amount of air to the interior of the inner shell 16. The vaporizing cup is located between the three fuel rings and depends below the bottoms of those rings. The wall portions 21 of the cup are formed by the adjacent portions of the outer wall 12 of the rings, and these portions are of a height which corresponds to the level of the shoulders 19 of the channels. Between these wall portions are connecting wall portions 22 which extend from one ring to the adjacent one, and on the inner surfaces of these wall portions 22 are shoulders or ledges 23 of the same height as the shoulders or ledges 19 and the tops of the wall portions 21. Leading downwardly from the bottom of the vaporizing chamber is a threaded opening 24 adapted to receive the usual oil supply pipe, not shown. Leading from the vaporizing chamber, and located at a level below the bottoms of the fuel grooves, are radiating conduits 25, and these conduits respectively open into the several channels 17 intermediate the ends of these channels. The openings between the channels and the conduits are designated generally 55

by the numeral 26. The bottoms of these conduits are preferably inclined downwardly from the openings 26 to the bottom of the vaporizing cup in order to facilitate cleaning of the conduits. If desired, the casting forming the base 5 may have suitable braces 27 between the oil rings.

The cup and the channels are adapted to be closed at their tops by suitable closure means 10 which may take the form of a cover, such as shown in Fig. 4. This cover, which is preferably formed by stamping the same from sheet metal, is provided with a central portion 30, corresponding generally to the cross section of the cup, and radiating arms 31 adapted to rest upon the ledges 15 of the channels, and which channels also radiate with respect to the center of the cup. With 20 this arrangement, it will be observed that the vaporizing cup is in communication with the central portions of the channels only through the conduits 25, and each channel is in communication with its respective fuel groove at the ends of the channel and at diametrically opposite points of the groove.

In operation, the burner is lighted in the usual manner and, to facilitate lighting, the ordinary starting wicks, located in the fuel grooves, may be employed, such wicks, however, not being shown, as they are not necessary and they are 30 old and well-known in the art. After the burner is in operation, the fuel, such as kerosene, is admitted to the vaporizing chamber and flows therefrom in the form of vapor through the conduits and the openings 26 of the central portions of 35 the radiating channels 17. The vapor admitted to each channel then flows towards the opposite ends of the channel and into the fuel grooves at diametrically opposite points. The vapor admitted to the grooves at such points will flow 40 about the grooves. The vapor admitted to the fuel grooves will rise into the combustion space between the shells 15 and 16 where it will be properly mixed with air so that a clear blue flame will result, complete combustion taking 45 place. It is observed that, with my improved arrangement, the oil vapor will be admitted to the fuel grooves at spaced points in each groove and in the correct proportions, and sufficient air will be admitted through the openings 26 and about 50 the several rings in order to insure the proper mixture of vapor and air within the combustion chambers, which means that the apparatus will operate with maximum efficiency and give off an intense heat. The burner may be very readily 55 cleaned after removal of the shells and the cover for the channels and vaporizing cup. When the cover is removed, the full lengths of the channels are open to view and ready access is had to the vaporizing cup. The conduits 25 may be readily 60 cleaned by inserting a suitable tool thereinto through the openings 26 in the bottoms of the channels. There is thus provided a very compact, highly efficient burner at a relatively low cost of manufacture and installation, and one which requires but little attention, and one which 65 may be very easily and readily cleaned when desired.

As many changes could be made in the above 70 construction and many apparently widely different embodiments of this invention could be made without departing from the scope thereof, it is intended that all matter contained in the above description or shown in the accompanying drawings shall be interpreted as illustrative and not 75 in a limiting sense.

It is also to be understood that the language used in the following claims is intended to cover all of the generic and specific features of the invention herein described and all statements of the scope of the invention which, as a matter of language, might be said to fall therebetween. 5

I claim as my invention:

1. In an oil burner of the character described, a plurality of ring-like members each having an annular fuel groove in its upper surface, each of 10 said members having a diametrically extending passage communicating at its opposite ends with a respective fuel groove, a cup about which said members are angularly spaced apart, and conduits radiating from said cup and leading to the 15 central portions of said passages.

2. In an oil burner of the character described, an integral base having a centrally located cup and a plurality of ring-like members angularly 20 spaced about said cup and each having an annular fuel groove in its upper face, the outer walls of said grooves forming portions of the walls of said cup, each of said ring-like members having a diametrically extending portion forming a channel 25 communicating at its opposite ends with the fuel groove, said cup having its bottom disposed below the bottoms of said oil grooves, and conduits leading from said cup at a point below the 30 bottom of said grooves to the central portions of said channels.

3. In an oil burner of the character described, a plurality of ring-like members each having an annular fuel groove in its upper face, each groove having an inner wall and an outer wall, a cross 35 bar within each ring-like member and having a channel communicating at its opposite ends with the groove in said member, a cup about which said members are angularly spaced apart and having wall portions formed by the outer walls of said fuel grooves, said cup depending below 40 said members, and conduits leading from the lower portion of said cup to the central portions of 45 said channels.

4. In an oil burner of the character described, an integral base having a centrally located cup and a plurality of ring-like members angularly 50 disposed about said cup, each ring-like member having an annular fuel groove in its upper face provided with an inner wall and an outer wall, each of said members also having a diametrically 55 extending cross bar provided with a channel communicating at its opposite ends with the groove of the respective member, said cup having wall portions formed by the outer walls of said fuel 60 grooves, and conduits leading from the lower portion of said cup to the central portion of said channels, the bottoms of said conduits being inclined 65 downwardly towards the bottom of said cup.

5. In an oil burner of the character described, a base having a centrally located cup provided 70 with an inlet and a plurality of ring-like members angularly spaced about said cup and each having a fuel groove in its upper face, each of said members having a diametrically extending open top channel communicating at its ends with a respective fuel groove, conduits leading from 75 said cup to said channels, and closure means for covering the top of said cup and the tops of said channels.

6. In an oil burner of the character described, a base having a centrally disposed open top cup and a plurality of ring-like members angularly 80 spaced about said cup, each of said members having an annular fuel groove in its upper face pro- 85

vided with an inner wall and an outer wall, each of said members also having a diametrically extending open top channel communicating at its opposite ends with the fuel groove with which it is associated, said channels being in radiating relation with respect to said cup, conduits connecting said cup to the central portions of said channels, and a cover having a central portion closing the top of said cup and arm portions covering said channels.

7. In an oil burner of the character described, a base having a vaporizing cup, a plurality of continuous fuel grooves angularly positioned about said cup and provided with a fuel passage associated with each fuel groove opening into said groove at spaced points therealong, and fuel conduits radiating from said vaporizing cup, each conduit connecting the interior of said cup with a respective fuel passage at a point in said passage intermediate the points at which said fuel passage opens into the associated fuel groove.

8. In an oil burner of the character described, a base having a vaporizing cup and provided with a plurality of continuous fuel grooves angularly positioned about said cup, a transverse fuel passage associated with each fuel groove and opening into the same at its ends, and fuel conduits radiating from said vaporizing cup, each conduit connecting the interior of said cup with a respective fuel passage intermediate the ends of the fuel passage.

9. In an oil burner of the character described, a unitary base having a vaporizing cup and provided with a plurality of continuous fuel grooves angularly positioned about said cup, a fuel passage associated with each fuel groove opening into said fuel grooves at spaced points therealong, and fuel conduits radiating from said vaporizing cup, each conduit connecting the interior of said cup with a respective fuel passage.
